METHOD OF FLUFFING A WET FLEECE OF STAPLE FIBER AND A DEVICE FOR CARRYING OUT SAME

Hans Thiele, Kassel, Germany, assignor to Spinnfaser Aktiengesellschaft, Kassel-Bettenhausen, Germany, a German corporation

Application December 1, 1954, Serial No. 472,454

Claims priority, application Germany December 9, 1953

15 Claims. (Cl. 19—65)

The present invention relates to a method of opening a wet fleece or mat of synthetic staple fiber in continuous operation and to a device for carrying out the method of the invention.

After being washed, the fleece is conducted through squeezing rollers which appreciably reduce the moisture content of the fleece. The final drying is carried out in an air drying device in which hot air is directed upon and through the moving fleece. This hot air serves to reduce the moisture content of the fleece to a very low percentage.

When the fleece has passed the squeezing rollers, the individual fibers of the fleece are very strongly matted or felted. The bottom side of the fleece is particularly dense; it often has a somewhat leathery surface. As a result, the hot air current of the subsequent air drier cannot readily penetrate into the interior of the fleece so that a substantial time is required until the fleece is thoroughly dried. This necessitates large sized air driers whereby the costs of the installation and the operational costs are materially increased.

Various attempts have been made to provide means for mechanically loosening the coherent and strongly felted wet fleece prior to the introduction thereof into the air drier to facilitate the penetration of the hot drying air.

One of the known means resides in conveying fleece layers of varying thickness to the hot air drier on a conveyor bearing needle combs. Above this conveyor distributing rakes or combs are mounted which are driven by eccentrically mounted levers and which serve further to loosen the upper side of the already broken-up or loosened fleece so that the fleece has an approximately uniform thickness when reaching the air drier. These aforescribed means have serious disadvantages. The individual fibers are pulled out of the fiber material and likely to be damaged by tearing. Furthermore, small fiber knots or nodes are formed in the fleece when the same is pulled forward in wet condition by the rakes or combs. These fiber knots cannot be dissolved during the subsequent treatment. The results are irregularities in the form of knobs and burls in the yarn or fabric spun from the fibers. Furthermore, due to the swelling of the fibers when being wet, flat cakes tend to be formed which cannot be dissolved without difficulty after drying. Staple fiber thus deteriorated makes a lifeless impression.

Another method of opening or loosening the fiber fleece prior to the final drying resides in passing the fleece through a bending, kneading, rubbing or compressing device in which the fleece is subjected to various mechanical operations and stresses working the fleece material. One of the best known devices of this type comprises meshed pairs of gears which force the fleece, when passed between the same, into a zigzag form whereby the fleece is kneaded and softened. However, devices of this kind have not been found to be satisfactory as the small flat cake areas of the fleece cannot be dissolved by the same. The combined application of the aforescribed mechan-

2

ical operations, namely bending, rubbing transversely to the direction of travel and the alternating upsetting or compressing in the direction of travel were also found not to be capable of sufficiently opening or loosening the wet fleece. In addition, the mechanical working as described has the disadvantage that as a result of the strong mechanical stresses to which the fleece material is subjected the individual fibers of the fleece are frequently and extensively damaged.

10 Further attempts have been made to vibrate the fleece by suitable vibrators or oscillators and to subject it transversely to its direction of travel to vibrations tending to divide the fleece in flat cake like parts. However, the formation of flat cakes is undesirable as already mentioned. Furthermore, the surface fibers of the fleece which come in direct contact with the vibrator are often appreciably damaged by the friction between said fibers and the respective parts of the vibrator.

Finally, methods and devices are known which employ 20 pulsating air currents. In such devices, the fiber band travelling through the device is subjected on both sides first to an excess atmospheric pressure and then to a sub-atmospheric pressure. It has also been proposed to subject one side of the fiber band to excess atmospheric pressure and the other side to sub-atmospheric pressure. As a result, the fleece travels through the device substantially along a sine line. However, the action of a device employing only a pressure differential is not sufficient since the individual fibers of the fleece are frequently coherent 25 to such an extent that the air cannot penetrate at all into the interior of the fleece.

30 One object of the present invention is to provide a novel and improved method of opening and fluffing a wet fleece or mat of synthetic staple fiber without appreciably damaging the individual fibers forming the fleece or mat.

Another object of the invention is to provide a novel and improved method of opening and fluffing the wet 35 fleece or mat by which the fleece or mat is so thoroughly loosened that only a comparatively short time is required 40 for completing the final drying operation in a hot air drier.

Still another object of the invention is to provide a 45 novel and improved method by which a highly uniform and fluffy fleece or mat is obtainable thereby greatly facilitating and expediting the subsequent operations to be performed on the fleece or mat, or more specifically on the fibers thereof.

The aforementioned and other advantages are attained 50 by subjecting the moving wet fleece or mat simultaneously to a purely mechanical bending operation and the action of air pressure. The combined simultaneous action of the bending operation and the air pressure affords the advantage that the air can deeply penetrate into scale like fissures formed in the fleece or mat by the bending operation thereby causing a rapid and thorough fluffing of the fibers.

55 The advantageous effect of the combined bending and air pressure action is further increased according to the invention, by supporting the fleece hollow upon or spaced apart from a solid support. Such spacing of the fleece permits the air fully to penetrate the fleece so that the fibers of the same are loosened both, in the direction toward the support and away from the same.

60 The result is a completely loose and fluffy fleece or mat, the fibers of which can be readily and thoroughly penetrated by the hot air of the drier into which the fleece or mat is subsequently guided. Furthermore, the fibers are not damaged during the opening or fluffing operation since they are not subjected to any mechanical action by rakes, combs, beaters, vibrators etc. as heretofore used for opening the fleece. Moreover, the individual fibers substantially retain their initial position

and length which facilitates the subsequent operations.

Other and further objects, features and advantages of the invention will be pointed out hereinafter and set forth in the appended claims forming part of the application.

In the accompanying drawing a preferred embodiment of the invention suitable for carrying out the method of the invention is shown by way of illustration and not by way of limitation.

Fig. 1 is a diagrammatic elevational view of a fleece working device according to the invention disposed between fleece squeezing rolls and a hot air drier.

Fig. 2 is a detail view of the device on an enlarged scale.

Fig. 3 is a further enlarged detail view to show the effect of the flow of pressure air upon the fleece.

Fig. 4 shows a modification of the spikes supporting the fleece.

Fig. 5 shows a fleece supporting spike roller on which the spikes are disposed in circumferential rows.

Fig. 6 shows a fleece supporting spike roller on which the spikes are disposed in staggered relationship, and

Fig. 7 is a perspective view of a spike roller supporting the fleece and of a bank of nozzles directing a flow of pressure air upon the fleece.

A fleece 1 made of synthetic staple fiber after leaving a washing device is passed between two squeezing rollers 2 and 3 which serve to reduce the moisture content of the fleece. An upwardly slanted endless conveyor 4 guides the fleece over a roller 5 of small diameter to a rotary spike roller 6. Roller 6 carries a plurality of spikes. These spikes may be slender frusto-conical spikes 10 as shown in Fig. 3 or slender conical spikes 10a as shown in Fig. 4. They may be arranged in circumferential rows according to Fig. 5 or in staggered relationship according to Fig. 6. Opposite to roller 6 and above the level of its rotational axis, nozzles 7 are provided communicating with a feed pipe 8 for pressure air. Fig. 7 shows a bank or row of nozzles 7 supplied with pressure air through the common feed-pipe 8. The nozzles are so disposed that they direct an air current against the fleece which impinges secantially upon the fleece when and while the same is passing over roller 6. After passing roller 6, the loosened or fluffed fleece is guided into a drying device 9 in which the fleece is further and finally dried by hot air.

The spike roller 6 may be in form of a hollow cylinder having perforations 11 distributed over its entire circumference. These perforations serve to suck off air. To limit the perforated area through which air can be sucked off, a suction pipe 12 may be provided within the cylinder which permits the influx of the outer air through the perforations 11 only through a pipe slot 13.

The device as hereinbefore described, operates as follows:

The fleece is delivered to the device in form of a wet densely felted fiber mass. It is first guided by conveyor 4 to small roller 5 and is comparatively sharply bent when passing under this roller whereby the outer fibers of the fleece lying on the side thereof opposite to roller 5 are slightly pulled apart or spread. During its travel from roller 5 to spike roller 6 the fleece is straightened but bent again and in opposite direction as before while being guided over roller 6, the diameter of which is also comparatively small. The spikes of roller 6 more specifically the tips thereof are so dimensioned that they cannot deeply penetrate into the fleece. Frusto-conical spikes have been found suitable. While the fleece is passing over roller 6 and is being bent in said opposite direction, the fibers on the side of the fleece which were on the inside when and while the fleece was passing over roller 5 are now lying on the outside of the fleece. As a result, these surface fibers are also pulled apart so that scale-like fissures are formed in the fleece surface as can best be seen in Fig. 3 without subjecting the

fleece to appreciable mechanical stresses. The pressure air directed by nozzles 7 upon the bent outside of the fleece in secantial direction can hence deeply penetrate into the scale-like fissures formed in the fleece. The air

current opens irregular channels within the fleece in the direction of movement of the fleece and at an angle thereto. A small portion of the air breaks through the sides of the fleece which is supported on the spikes, aided by the fissures on this side and the suction. But the major portion of the air remains in the loosened and fluffed fleece thereby facilitating the subsequent drying operation. As is evident, it is advantageous for the aforescribed action of the air current that the fleece is supported spaced apart from the body proper of roller 6 which is effected by the provision of the spikes particularly of spikes of frusto-conical or truncated shape. It is further evident that by the formation of fissures on both sides of the fleece effected by bending the fleece in opposite directions the fluffing of the fleece is materially increased. If the circumferential speed of the spikes is substantially equal to the rate of movement of the fleece, practically no force has to be transmitted from the spikes to the fleece. Accordingly, there is hardly any tendency for the spikes to penetrate into the fleece as the same presses upon the spikes substantially with its own weight only. As explained, the air current in coaction with the suction cause a loosening of the fleece in both directions, that is, toward roller 6 and also away from the same so that the fleece is thoroughly fluffed as indicated in Fig. 2. The result is that the wet fibers of the fleece tending to adhere to each other are separated to a very large extent and that consequently the hot air within drier 9 can penetrate the fleece and fully and quickly dry the same.

The pressure air delivered by nozzles 7 and penetrating the fleece can be conducted away by the suction means previously described. However, it is advantageous that these suction means are effective only within the range of the angle at which the pressure air impinges upon the fleece.

To increase the scaling or splitting effect of spike roller 6, it is advantageous, particularly for the treatment of heavier fleeces, to select the circumferential speed of roller 6 slightly higher than the moving speed of the fleece imparted to it by conveyor 4. Such differential speed assures that the outer fibers pulled apart and loosened by the action of roller 5 are not again compressed and flattened by roller 6. In the event that such differential speed is employed, a certain force is transmitted from the roller to the fleece. As a result, the spikes may slightly penetrate into the fleece, but this penetration is not sufficient adversely to affect the operation of the device.

The bending of the fleece and the simultaneous application of pressure air generally result in a sufficient loosening and fluffing of the individual fibers of the wet fleece to obtain a satisfactory further drying. In the event that the action of a single device as hereinbefore described, is not adequate several devices according to the invention may be provided in series arrangement.

The action of the device or devices according to the invention not only reduces the drying time required in the drier but also results in a more uniform and fluffier fleece made of synthetic staple fiber.

While the invention has been described in detail with respect to a certain now preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. The method of fluffing but retaining in fleece form

a moving wet fleece of felted synthetic staple fiber in continuous operation, which comprises the steps of bending and floatingly supporting successive portions of the moving fleece for opening fissures in the bent fleece portions and simultaneously directing an air current under pressure in secantial direction upon successive bent floatingly supported and fissured fleece portions.

2. The method of fluffing but retaining in fleece form a moving wet fleece of felted synthetic staple fiber in continuous operation, which comprises the steps of subjecting successive portions of the moving fleece to successive bendings in opposite direction for opening fissures on both sides of the fleece, floatingly supporting the successive portions when bent in one of said directions, and simultaneously directing an air current under pressure in secantial direction upon successive and floatingly supported bent fleece portions on the curved side thereof opposite the center of the respective bending.

3. In the method according to claim 2, the additional step of subjecting the floatingly supported fleece portions to a suction on the side thereof opposite to the one to which said air under pressure is applied.

4. A device for fluffing but retaining in fleece form a moving wet fleece of felted synthetic staple fiber in continuous operation, said device comprising a rotary bending means for bending the moving fleece to open fissures in the side thereof opposite said bending means, peripheral support elements on said bending means for floatingly supporting successive fleece portions, conveyor means for conveying the fleece to be fluffed to said bending means, the peripheral speed of said bending means being slightly in excess of the travelling speed of said conveyor means, and air blower means disposed opposite said bending means for directing an air current under pressure in secantial direction upon the fissured side of successive bent fleece portions when and while the same are supported by said support elements.

5. A device for fluffing but retaining in fleece form a moving wet fleece of felted synthetic staple fiber in continuous operation, said device comprising a rotary bending means for bending the moving fleece, said bending means including radially extending support elements supporting spaced apart limited areas of the fleece to provide free space on both sides of the fleece while the same is passing over said bending means, and air blower means including air nozzles disposed opposite said bending means and oriented to direct a jet stream of pressure air in secantial direction upon the fissured side of the fleece facing the air nozzles while and when the fleece is supported on said support elements.

6. A device according to claim 5, wherein the said rotary bending means comprise a spike roller supporting and guiding the fleece radially spaced from the body of the roller.

7. A device according to claim 6, wherein the spikes on said spike roller are disposed in rows. 55

8. A device according to claim 6, wherein the spikes on said spike roller are disposed on and distributed over the circumference of the roller in staggered relationship.

9. A device according to claim 5, wherein the said rotary bending means comprise a spike roller supporting and guiding the fleece radially spaced from the body of the roller, the spikes on said roller having a slender conical shape.

5 10. A device according to claim 5, wherein the said rotary bending means comprise a spike roller supporting and guiding the fleece radially spaced from the body of the roller, the spikes on said roller having a slender frustoconical shape.

10 11. A device according to claim 5, wherein the said rotary bending means comprise a hollow cylinder and a plurality of spikes radially extending from the outer cylinder wall for supporting and guiding the fleece radially spaced apart from said cylinder wall, the cylinder wall including a perforated wall portion situated in the area in which said secantial jet stream impinges upon the cylinder wall, and suction means for sucking air from the interior of the cylinder entering the latter through said perforations.

15 12. A device for fluffing but retaining in fleece form a moving wet fleece of felted staple fiber, comprising bending means for bending the moving fleece to open fissures in the side of the fleece opposite said bending means including supporting elements engaging and floatingly supporting the fleece at spaced apart limited areas to provide free space on both sides of the fleece while being supported by said supporting elements, and air blower means disposed opposite to said bending means for directing a current of air under pressure in secantial direction upon the fissured side of successive bent fleece portions when and while the same are supported by said supporting elements.

20 13. A device for fluffing but retaining in fleece form a moving wet fleece of felted staple fiber in continuous 30 operation, comprising first bending means for bending the moving fleece to open fissures in the side of the fleece opposite the said bending means, second bending means disposed posterior of the first bending means in the direction of movement of the fleece for bending the fleece in opposite direction to open fissures in the other side of the fleece, said second bending means having peripheral supporting elements engaging and floatingly supporting the fleece at spaced apart limited areas to provide free space on both sides of the fleece while being supported on said 35 supporting elements, and air blower means disposed opposite to said second bending means for directing a current of air under pressure in secantial direction upon the adjacent fissured side of successive bent fleece portions when and while the same are supported on said supporting elements.

40 14. A device according to claim 13, wherein said first bending means comprise a roller having a smooth peripheral surface, and wherein said second bending means comprise a spike roller.

45 15. A device according to claim 14 and further comprising conveyor means conveying the fleece to said smooth roller.
